(57) **CLAIM**

The ornamental design for a translucent golf hole cup with removable sleeve, as shown and described.

DESCRIPTION

FIG. 1 is a top plan view of the translucent golf hole cup with the sleeve removed;

FIG. 2 is a cross-sectional view taken on line 2—2 of FIG. 1;

FIG. 3 is a bottom plan view of FIG. 1;

FIG. 4 is a top plan view of the translucent golf hole cup with the sleeve in place;

FIG. 5 is a cross-sectional view taken on line 5—5 of FIG. 4;

FIG. 6 is a bottom plan view of FIG. 4;

FIG. 7 is a top plan view of the translucent golf hole cup with the sleeve partially in place;

FIG. 8 is a cross-sectional view taken on line 8—8 of FIG. 7;

FIG. 9 is a bottom plan view of FIG. 7;

FIG. 10 is a bottom perspective view of FIG. 1;

FIG. 11 is a bottom perspective view of FIG. 4; and,

FIG. 12 is a bottom perspective view of FIG. 7.
